ROLLER SKATE WHEEL MOUNTING

Paul J. Owsen and Peter Owsen, Dearborn, Mich.

Original application April 25, 1950, Serial No. 157,928. Divided and this application July 28, 1951, Serial No. 239,101

3 Claims. (Cl. 280—11.28)

1

This application constitutes a division of our application Serial No. 157,928, filed April 25, 1950.

The present invention relates to a roller skate wheel mounting adapted for use on a roller skate used for skating on hard surfaces, such as floors, pavements and the like.

It is an object of the present invention to provide a skate of this class having the traction members so mounted that jars and shocks received thereby are not transmitted to the skater.

Another object of the invention is the provision of a skate of this class of a mounting for the traction members so arranged and constructed that a flexing of the main body of the skate relative to the traction members and a tilting of the axes of the traction members relative to the longitudinal center of the main body may be easily and quickly effected thus facilitating the steering of the skate.

Another object of the invention is the provision of a skate of this class which may be economically manufactured, which may be durable, light and highly efficient in use.

Other objects will appear hereinafter.

It is recognized that various modifications and changes may be made in the detail of structure illustrated and it is intended that the present disclosure shall be considered but the preferred embodiment.

Forming a part of this specification are drawings, in which:

Fig. 1 is a top plan view of a roller skate showing the invention applied,

Fig. 2 is a longitudinal sectional view taken on line 2—2 of Fig. 1,

Fig. 3 is a sectional view taken on line 3—3 of Fig. 1,

Fig. 4 is a rear end elevational view of the invention,

Fig. 5 is a central longitudinal sectional view of a modified form with parts shown in elevation and parts broken away,

Fig. 6 is a sectional view taken on line 6—6 of Fig. 5,

Fig. 7 is a perspective view of a support used in the invention.

A rear heel engaging plate 46 is provided with an upwardly extending flange 47 at its rear end. Secured to this flange 47 are the straps 48 which are adapted to be fastened around the foot of the user in the usual manner. Secured to the bottom face of the plate 46 and projecting downwardly therefrom is the bar 48a having the side walls 49 and 50 each provided with the inwardly turned flange 41 which are spaced apart. This

2

bar 48a slidably engages as a snug fit in the member 22 and may be secured in fixed relation thereto at various positions of longitudinal movement by means of the bolt 52 and wing nut 53. This bolt 5 is projected through an opening 54 formed in the member 22 and engaging at its head 55 with a washer 56. The wing nut 53 bears against the lock washer 37. Formed on the upper face of the bar 48a are graduations 58 so as to indicate the various lengths of adjustment of the plates 21 and 46 to accommodate shoes of various sizes.

Mounted on the bottom of the forward end of the member 22 is a retainer comprising the plate 59 having an opening 60 formed substantially therein. The ends of the plate 59 are provided with the upwardly turned flanges 61 and 62 each of which is again angularly turned to provide the flanges 63 and 64 respectively. These flanges 63 and 64 engage the end surface of the member 22 and are suitably attached thereto by means of bolts, rivets, spot welding or the like.

A similar plate 59 designated generally by the numeral 59a is mounted on the end surface of the rear end of the bar 48. The mounting and structure of the wheels at both ends of the skate are the same so that a description of one will suffice for both.

As shown on the drawings there are four traction wheels and at each of these wheels there is mounted a spring embodying the horizontally disposed portion 65 having the angularly upwardly turned end 66 projecting through one of the openings 67 formed in the plate 59. Positioned beneath the plate 59 is a clamping plate 68 having an upwardly directed flange 69 at each end, each flange being provided with a recess 70 in which the member 65 engages. This plate 68 is also provided with an opening 71 and a bolt 72 extending through the opening 71 and through the opening 60 and is provided with a nut 73 whereby the plate 68 may serve to clamp the portion 65 in engagement with the plate 59 and prevent disengagement of the angularly turned end 66 from the opening 67. This portion 65 is carried by the diagonally upwardly directed portion 74 which extends upwardly from a coil 75, the parts 65, 74 and 75 being formed from a single piece of resilient material. The nut 73 is enclosed in the inverted cap shaped housing 76 which has, on its bottom a centrally positioned downwardly projected boss 77 which seals in a recess 78 formed in the upper face of a resilient yielding block 79 preferably formed from rubber. This block 79 is pro-

vided at its lower end with a recess 80 in which engages an arcuate rib or bulge 81 extending upwardly from the metal plate 82. This arcuate bulge or rib 81 seals over a spacing tube 83 through which extends a bolt 84 having a nut 85 at one end.

By mounting the traction members in this manner it is believed obvious that an easy steering of the skate becomes possible as the traction members may tilt vertically relative to the shoe supporting plate and also transversely.

In the form shown in Fig. 5 instead of providing a separate plate such as the plate 46 we provide a plate 120 which is formed integral with the bar 148 which corresponds to the member 48a of the form shown in Fig. 1. This member 148 telescopes in the member 121 which corresponds to the member 21 shown in Fig. 2. Projecting downwardly from the member 120 at opposite sides is a side flange 149 which serves as a reinforcement.

The bottom 151 of the member 121 has the downwardly directed portion 152 terminating in the upwardly inclined portion 153 which serves as a support and which is provided with an opening 154 through which is projected the head 155 formed in the plug 156 which corresponds to the plug 79 shown in Fig. 2. A cap 157 is fitted over the lower end of the plug 156 and has the inwardly pressed portion 158 which is arcuate in cross section to receive the spacer 159 which corresponds to the spacer 83 shown in Fig. 3. A spring embodying the portions 174 and 165 which correspond to the parts 74 and 66 shown in Fig. 2 is provided with the coil 175 corresponding to the coil 75 shown in Fig. 2 and Fig. 3. The upwardly turned end 166 corresponding to the part 66 shown in Fig. 2 is projected through an opening 168 formed in the plate 161. A bolt 162 is projected through this plate 161 and through a clamping plate 164 so that the spring mounting is thus clamped securely on the plate 161. The primary difference between this type of mounting the front wheels of the skate from that shown in Fig. 2 is that the member 156 is inclined to the vertical so that thrusts delivered against the traction wheels are transmitted more longitudinally of the member 156 than they are of the member 79.

Similarly the rear wheels are mounted so that the block 178 of rubber or other yieldable material is also at an incline and provided at its bottom with a cap 179 having the arcuate recess 180 formed therein to receive the spacer 181. To accomplish this we provide a boxlike supporting structure having the rear wall 182, the inclined forward wall 183 and the side walls 184 and 185 extending outwardly from each of which is a flange 186 which is spot welded or otherwise secured to the under surface of the member 20. Openings 187 are formed in the bottom 188 of this structure through which projects the upwardly turned end 189 of the spring arm 190. A downwardly inclined portion 191 at the forward end of the plate 188 is provided with the opening 192 through which is projected the head 193 of the block 178. A bolt 194 is projected through the plate 188 and through the clamping plate 195 so that the spring arm 190 may be securely clamped to the plate 188.

The modification is made primarily to locate the member 178 in the inclined position so that the thrusts delivered thereto will be generally longitudinally thereof.

We have eliminated in the form shown in Fig. 5

the wing nut shown in Fig. 2 and instead of this construction for retaining the members 48 and 21 in their various adjusted positions we mounted within the member 148 the washer 196 through which is projected the bolt 197 which also extends through the members 121 and 141 and through the washer 198. The lever 199 is provided with a head 201 through which the bolt 197 projects, this head 201 being of a flat disc-like construction and provided with the downwardly projecting ribs or corrugations 202 which are adapted to co-act with the corrugated spring washer 203 held in position by the nut 204. When the lever 199 is rocked so that the corrugations 202 will mesh in the corrugations 203 the members 121 and 148 may be moved longitudinally of each other. When the lever 199 is swung to the position shown in Fig. 6 so that the corrugations 202 ride out of registration with the corrugations or recesses 203 a clamping effect will be obtained so that the members 121 and 148 will remain in fixed position. The tension of the members 201 and the spring washer may be adjusted by threading or unthreading the nut 204. By this method of securing the members 121 and 148 in fixed position we have provided a simple and effective means whereby the clamping relation between these parts 121 and 148 may be easily effected and easily and quickly released without resorting to the use of a screw such as shown in Fig. 2.

Experience has shown that with a roller skate constructed in the manner herein described in addition to obtaining a substantially noiseless operating roller skate on which the user will be relieved materially of the jars and shocks customarily encountered in roller skating, the structure is one which is very durable, may be economically manufactured and which may be easily and quickly adjusted to fit various sized shoes and easily and quickly fastened on the shoe and removed therefrom.

What we claim is:

1. In a roller skate of the class described, a supporting body for supporting the shoe of the user; a spring mounted at one end of said body and depending therefrom; traction wheels; a hub for each of said traction wheels; a tubular member extending inwardly from the hub; a yieldable sleeve embracing said tubular member; and a portion on the lower end of said spring embracing said tubular sleeve; a shaft projected through the hub and the tubular member; and a yieldable block positioned between said shaft and said body and engaging the same at its opposite ends.
2. In a roller skate of the class described, a supporting body for supporting the shoe of the user; a pair of springs each connected to said body adjacent the end thereof and depending therefrom in spaced apart relation; a pair of traction wheels one adjacent each side of said body, below the same; a hub on each of said wheels; a tubular portion projecting inwardly from each of said hubs; a sleeve of resilient material embracing the tubular portion; a coil on the lower end of each of said springs embracing a yieldable sleeve; a shaft projected through said hubs and said tubular portions; and a spacing sleeve on said shaft between said resilient sleeves for maintaining the traction wheels in spaced apart relation; and a block of resilient material engaging at one end said spacing sleeve and at its opposite end said body for resisting approach of said spacing sleeve toward said body.
3. In a roller skate of the class described, a

supporting body for supporting the shoe of the user; a pair of springs secured at one of their ends to said body adjacent the end thereof at opposite sides thereof; a coil formed on the lower end of each of said springs; a pair of traction wheels; a shaft projecting through said traction wheels; said coils embracing said shaft and yieldable material positioned between the inner surface of said coils and said shaft and engaging the inner surface of the coils; and a spacer embracing said shaft for maintaining said wheels in spaced apart relation; and a resilient member positioned between said wheels and engaging at one end with said body and at its opposite end with said spacing sleeve for resisting approach 15 of said axle toward said body.
